UNITED STATES PATENT OFFICE.

WILLIAM A. MARITZEN, OF SAN MATEO, CALIFORNIA.

FIREPLACE HEATING DEVICE.

1,314,968.

Specification of Letters Patent.

Patented Sept. 2, 1919.

Application filed March 4, 1918. Serial No. 220,266.

To all whom it may concern:

Be it known that I, WILLIAM A. MARITZEN, a citizen of the United States, residing at San Mateo, in the county of San Mateo and 5 State of California, have invented certain new and useful Improvements in Fireplace Heating Devices, of which the following is a specification.

The present invention has to do with improvements in heating devices as particularly adapted for use in fireplaces, the primary object being to provide a simplified structure which is applicable to standard fireplaces, provision being preferably made for adjusting the parts so as to properly fit the customary recess constructions. It may here be stated that one of the serious defects of a fireplace is that practically all of the heat which is produced by the fire built therein 10 escapes up the chimney flue so that little benefit, as regards the room containing the fireplace, is derived from its use aside from the heat obtained from direct radiation from the fire, which is, as well known, very slight 15 indeed.

My aim has been to overcome this difficulty by providing a radiating body embodying a heat conveying chamber which is so formed and arranged as to cause the air 20 passing therethrough, which is heated by the fire, to be directed back into the room instead of allowing its passage into the flue of the chimney.

Secondarily my device contemplates provision for the maximum heating surface for 25 efficiency acting upon the air utilized for heating the room containing the device.

These and such other objects as may hereinafter appear are attained by the novel 30 construction, combination and arrangement of parts to be hereinafter specifically described and claimed. Reference will now be had to the accompanying drawings forming a part of this specification, wherein:

Figure 1 is a front elevation of a fireplace showing the application of my invention thereinto;

Fig. 2 is a vertical sectional view of the fireplace showing the heating device in end elevation.

Fig. 3 is a vertical sectional view through the heating device itself; and

Figs. 4 and 5 are transverse sections taken on the planes indicated by the lines 4-4 55 and 5-5 of Fig. 3, respectively.

Throughout the following detail descrip-

tion and on the several figures of the drawings, similar parts are referred to by like reference characters.

Referring to the drawing, 1 designates a conventional fireplace construction which embodies a recess in the wall with a connecting flue 2 in the chimney. Into the fireplace recess the device which forms the subject matter of this invention is inserted. 60 One of the particular features of my device is its unitary structure, complete in itself, capable of being inserted and removed from the fireplace, and not depending upon the walls of the recess to form the confines of 65 70 the heating chamber.

The device consists of a metallic body preferably, which is tubular in construction, substantially rectangular in cross section, embodying the base portion 3, and a vertically extending portion 4 connecting with the horizontal portion 5. The fire is built over the horizontal base portion 3 just referred to and this portion is preferably narrower than the vertical portion, as will 75 80 be observed by reference to Fig. 1, so as to afford proper space to dispose the andirons at each side thereof where such devices are used. However, the fire may be built directly upon this horizontal portion and the 85 middle is suitably supported so as to sustain the weight and to prevent distortion by means of posts or pillars 6. These pillars not only have a supporting function but are designed to assist in heating the air which 90 intakes through the forward entrance of this base portion which contacts as it passes through into the rear connecting portion 4 hereinbefore referred to. The rear portion just mentioned conforms preferably to the 95 usual angular shape of the rear wall of the fireplace recess and it includes an adjustable connection indicated at 7.

In other words, a separate section is provided which fits into the lower part of the 100 portion 4, suitable fastening means being provided to hold the section at adjusted position. It follows that the horizontal portion 5 will be properly adjusted for the height of the particular fireplace, in addition to which the horizontal portion is provided with the adjustable section 8 which enables adjustment for the proper depth of the recess. At the angle between the vertical portion 4 and the horizontal portion 5 105 110 the metal of the forward wall of the device is pressed outwardly so as to provide

oppositely inclined planes designated 9 which constitute a deflector. The deflector not only affords an increased heating surface for acting upon the air passing through 5 the device but directs the smoke and by-products laterally of the upper portion directly adjacent to the flue so that the aforesaid smoke and by-products pass about the upper portion into said flue. Since the upper 10 portion mentioned overhangs the fire in immediate proximity thereto, a very efficient heating action as regards the air passing through the device is obtained. I increase the efficiency of the heating action by corrugating the forward wall of the vertical portion as indicated at 10. As hereinbefore premised, the air passes from the room into the forward part of the base portion 3 where it is subjected to the heat from the fire resting above the same and the heat of the pillars 6, then passes up the vertical portion 4 and out the horizontal portion which, for the purposes of this description will be called the discharge chamber as distinguished 20 from the receiving chamber in the base 3. By using the simple article herein described the air from the room is heated and passed back into said room instead of being allowed to pass up the flue.

30 Since my heating device is a unitary structure it will be obvious that it would adequately perform the air heating function even when it is not positioned within a fireplace because it does not require the walls 35 of the fireplace to constitute the confining means for the air conduit and this is a special feature because when desired it may be removed from the fireplace and the walls will have been protected against the discoloration and smudging of that portion which 40 is covered by the invention and which is directly subjected to the heat and smoke of the fire.

Having thus described my invention, 45 what I claim as new is:

1. A fireplace heating device of the class described comprising a unitary tubular conduit complete in itself, said conduit having a horizontal base portion arranged with its mouth adapted to receive air from the room 50 in which the fireplace is built, said conduit extending vertically at the rear of the base portion and outwardly of the fireplace at the top of said vertical portion so as to discharge the air back into the room aforesaid 55 after being subjected to the heat during its passage through the conduit, the front wall of the conduit adjacent to the top portion being pressed outwardly to form an oppositely inclined deflecting surface at this 60 point for shunting the products of combustion about the sides of the conduit and into the flue of the fireplace, the vertically and outwardly extending portions of the conduit 65 overhanging the base portions so as to

be directly heated by the fire imposed upon the base portion.

2. A fireplace heating device of the class described comprising a unitary tubular conduit complete in itself, said conduit having a horizontal base portion arranged with its mouth adapted to receive air from the room in which the fireplace is built, said conduit extending vertically at the rear of the base portion and outwardly of the fireplace at the top of said vertical portion so as to discharge the air back into the room aforesaid after being subjected to the heat during its passage through the conduit, the front wall of the conduit adjacent to the top portion being pressed outwardly to form an oppositely inclined deflecting surface at this point for shunting the products of combustion about the sides of the conduit and into the flue of the fireplace, the vertically and outwardly extending portions of the conduit consisting of telescopic sections, including means to hold one of said sections at adjusted position, and the base portion having supporting posts arranged in spaced relation therewith to assist in heating of the air as it passes through the conduit in circulation.

3. A fireplace heating device adapted to be disposed bodily in an ordinary fire place, the same comprising a horizontal base portion adapted to rest upon the base of the fireplace, said base portion being hollow and open at its front end to provide a mouth to receive air from the room in which the fireplace is located, pillars located in said hollow base portion to strengthen the same and forming heat radiating elements supporting the top of said base portion upon which a fire may be built, the base portion of the conduit having a vertically extending portion projecting from its rear end and formed with an outwardly projecting portion or extension adapted to fit across the top portion of the fireplace, said outward extension being considerably narrower than the vertical portion from which it projects so as to permit the passage of products of combustion past its sides up into a chimney above the fireplace.

4. A fireplace heating device adapted to be disposed bodily in an ordinary fireplace, the same comprising a horizontal base portion adapted to rest upon the base of the fireplace, said base portion being hollow and open at its front end to provide a mouth to receive air from the room in which the fireplace is located, said hollow base portion having a hollow vertical portion projecting upwardly therefrom and practically a continuation thereof, the vertical portion being inclined outwardly so as to extend above the base portion and being made in sections adjustable to enable the heater to conform with fireplaces of different sizes vertically,

the said outwardly extending portion having at its upper end a horizontal continuation thereof and the latter being of sectional form to accommodate for fireplaces 5 of different depths.

5. A fireplace heating device adapted to be disposed bodily in an ordinary fireplace, the same comprising a horizontal base portion adapted to rest upon the base of the 10 fireplace, said base portion being hollow and open at its front end to provide a mouth to receive air from the room in which the fireplace is located, said hollow base portion having a hollow vertical portion projecting 15 upwardly therefrom and practically a continuation thereof, the vertical portion being inclined outwardly so as to extend above the base portion and being made in sections adjustable to enable the heater to conform

with fireplaces of different sizes vertically, 20 the said outwardly extending portion having at its upper end a horizontal continuation thereof and the latter being of sectional form to accommodate for fireplaces of different depths, the front wall of said vertical 25 portion and a part of the front wall of the outwardly extending portion of the conduit leading from said vertical portion being corrugated to provide an extending radiating surface above the base portion, and the 30 heater being formed with an oppositely inclined deflecting surface approximately at the angle formed by the upper extremity of the heater and the outwardly inclined portion above described. 35

In testimony whereof I affix my signature.

WILLIAM A. MARITZEN.
